UNITED STATES PATENT OFFICE.

JOSEPH E. FELLER, OF BROOKLYN, NEW YORK.

STARTING AND SPEED-LIMITING DEVICE FOR ELECTRIC MOTORS.

1,367,592.

Specification of Letters Patent.

Patented Feb. 8, 1921.

Application filed April 13, 1917. Serial No. 161,765.

To all whom it may concern:

Be it known that I, JOSEPH E. FELLER, a citizen of the United States, residing at Brooklyn, in the county of Kings, State of New York, have invented certain new and useful Improvements in Starting and Speed-Limiting Devices for Electric Motors, of which the following is a full and clear specification.

10 This invention relates to means for automatically controlling the operation of electric motors and has for its primary object to provide an improved operating system, according to which the acceleration of the 15 motor during the starting period is made to depend upon the current input to the motor and not upon the line voltage. The present invention contemplates an operating system for electric motors in which an abnormally 20 weak field, an open circuit in the field or its connections, an open circuit in the field rheostat, or a faulty contact in the field circuit, causes the motor to stop, if running, and if the motor is not running, prevents it being 25 started. One of the objects of the present invention is to provide improved means for accomplishing these results without the blowing of fuses, opening of circuit breakers, and without damage to the motor or to 30 any of the apparatus. Another object is to provide improved means for automatically regulating the sensibility of the circuit breaker to correspond to conditions at starting and while running, thus affording proper 35 protection to the apparatus under all conditions. Other and further objects will appear in the specification and be pointed out in the appended claims, reference being had to the accompanying drawings which exemplify my invention in a preferred embodiment.

In the drawings:

Figure 1 is a wiring diagram according to this embodiment of my invention;

45 Fig. 2 shows a portion of this diagram on an enlarged scale with the parts in different positions.

Referring more particularly to the drawings, the parts will be referred to in the order in which they occur in the various circuits. Thus in the present embodiment of my invention, a positive main 1 is connected to a wire 2 from which extends a wire 3 leading to one brush of an armature 4 of a fractional horse power pilot motor, the other brush of said armature being connected by

a wire 5 to a fixed contact 6. A movable contact 7 is yieldably mounted on one arm 8 of a lever which is pivotally mounted at 9 and connected by a wire 10 to a fixed contact 11 with which co-operates a contact 12, yieldably mounted on one arm 13 of a lever pivoted at 14 and acted upon by a tension spring 15. A wire 16 leads from the pivot 14 of lever 13 to a fixed contact 17. A wire 18 leads from the contact 17 to a fixed contact 19. A contact 20 is adapted to be yieldably pressed against the fixed contact 19 by a lever arm 21 which carries a pin 22 with which engages the hook arm 23 of a lever fulcrumed at 24, a wire 25 leading from the fulcrum 24 to the negative main 26. A branch wire 27 leads from the positive main 1 to a coil or magnet 28, the other terminal of said coil or magnet being connected by a wire 29 to a fixed contact 30 which is spaced from the contact 17 and adapted to be connected thereto by a pivotally mounted switch lever 31. The line wire 2 is electrically connected to the journal 32 of a rheostat arm 33 which is adapted to move successively over the contacts 34 for cutting out successive portions of the resistance. The last contact 34 is connected by a wire 35 to one terminal of a field winding 36 of the pilot motor, the other terminal of the winding 36 being connected by a wire 37 to a wire 38 which leads to one end of an overload winding 39. The other end of the winding 39 is connected by a wire 40 to one brush of the armature 41, 90 the other brush of said armature being connected by a wire 42 to an oscillatory contact 43 which is adapted to be magnetically operated by the coil or magnet 28 to be moved into engagement with a fixed contact 44 connected with a blow-out coil 45, the other end of the blow-out coil 45 being connected by a wire 46 to the negative main 26. Connected to the wire 2, is a solenoid or winding 47, which when energized, magnetically clutches the rheostat arm 33 to the gear 51 which is driven by the pilot motor through the worm 50. A wire 48 leads from coil 47 to the field winding 49 of the pilot motor, said field winding 49 being also connected to the negative line leading from the pilot motor armature and including contacts 11 and 12 and circuit breaker contacts 19 and 20. Whenever the rheostat arm 33 is magnetically clutched to the worm gear 51, said arm is caused to 105 travel over the contacts 34 in succession until it reaches a contact 52 which is connected by

a wire 53 to one terminal of a magnet 54, the other terminal of said magnet being connected by a wire 55 to the wire 10 hereinbefore referred to. Whenever the magnet 54 is energized, it attracts an armature lever 56 which swings about a pivot 57 and is connected to the wire 38. The armature 56 carries a contact 58 which is brought against the fixed contact 59 to which is connected one end of a blow-out coil 60, the other end of said blow-out coil being connected to a line wire 61, leading from the positive main 1. A wire 62 leads from the positive wire 2 to a field rheostat 63 which is connected by another wire 64 to a magnet 65. A wire 66 connects magnet 65 to field winding 67 of the main motor, said field winding being connected by the wire 68 to the negative line from motor armature 41. An armature 69 is connected to the lever 13 and when attracted by magnet 65 closes contacts 11 and 12. The armature lever 56 is provided with a laterally projecting arm 69 adapted to depress a reciprocable bolt 70 which engages one arm 71 of a lever pivoted at 72, the other arm 73 of said lever being adapted at its extremity to engage one arm 74 of the lever pivoted at 9, the energization of the magnet 54 being therefore adapted to open the contacts 6 and 7 and thereby interrupting the operation of the pilot motor. A pendulum-like lever 75 is pivoted at 76 to the lever arm 73 and has a deflected end 77 which carries an adjustable abutment 78 for determining the lower limit of an armature lever 79 which is pivoted at 80 and adapted to be raised by the overload solenoid 39 when the degree of energization reaches a certain predetermined undesirable amount. A scale plate 81 may be provided for indicating the amperage within the solenoid coil 39 which will result in a lifting movement to the armature 79. Whenever the armature 79 is thus lifted it raps the arm 82 of the lever pivoted at 24 and thereby depresses the other arm 23 to disengage it from the pin 22. Thereupon the arm 21 which carries the yieldably mounted contact 20 is swung about its center 83, by a spring 84 until it strikes a stop 85. A handle 86 adapts the lever 21 to be returned to normal position for resetting the circuit breaker.

The operation of my improved system may be briefly described as follows: Suppose both motors to be at rest, the switch 31 being in the position shown in Fig. 1, the contacts 11 and 12 shown in Fig. 1, being opened, and the parts shown in Fig. 2 being in full line positions. When the switch 31 is moved to bridge the gap between contacts 30 and 17, the following circuit is established: positive main 1, wire 27, magnet 28, wire 29, contact 30, switch 31, contact 17, wire 18, contacts 19 and 20, arm 21, pin 22, lever 23, pivot 24, wire 25, and negative main 26. Magnet 28

being energized, attracts armature contact 43, thus closing the following circuit: positive main 1, wire 62, rheostat 63, wire 64, magnet 65, wire 66, field winding 67 (of the main motor), wire 42, armature contact 43, contact 44, blow-out coil 45, wire 46, and negative main 26. This circuit energizes magnet 65, which operating on armature 69, closes contacts 11 and 12. At the same time field winding 67 is energized. By closing the contacts 11 and 12, the following circuit is established: positive main 1, wire 2, wire 3, pilot motor armature 4, wire 5, contacts 6 and 7, lever 8, pivot 9, wire 10, contacts 11 and 12, lever 13, pivot 14, wire 16, wire 18, contacts 19 and 20, arm 21, pin 22, lever 23, wire 25, and negative main 26. Simultaneously a branch circuit is established through wire 2, winding 47, wire 48, field winding 49 of the pilot motor and the negative line leading from pilot motor armature 4. The energization of winding 47 serves to effect a magnetic clutch between the hub portion of rheostat arm 33 and the gear 51 so that the rheostat arm 33 is slowly moved in a clockwise direction by the pilot motor. As the rheostat arm moves in a clockwise direction, the following circuit is made: positive main 1, wire 2, arm 33, contacts 34 and resistance connected thereto, wire 35, field winding 36 of the pilot motor, wire 37, wire 38, circuit breaker coil 39, wire 40, main motor armature 41, wire 42, contacts 43 and 44, blow-out coil 45, wire 46, and negative main 26. As the main motor accelerates, the angular speed of rheostat arm 33 will depend upon the amount of current in the pilot motor coil 36 which is connected up in series with the circuit breaker coil 39 and armature 41. It will be seen therefore that the speed of the pilot motor will be regulated by the current input to the armature of the main motor. When the rheostat arm 33 has reached contact 52, a shunt circuit is established through wire 2, rheostat arm 33, contact 52, wire 53, magnet 54, wire 55, and negative line from wire 10. The energization of magnet 54 attracts armature 56 and closes contacts 58 and 59 to establish a main motor circuit independently of the pilot motor, as follows: positive main 1, wire 61, blow-out coil 60, contacts 59 and 58, arm 56, wire 38, winding 39, wire 40, armature 41, and negative line from the main motor. At the same time, lever 73 is shifted to full line position shown in Fig. 1 which opens contacts 6 and 7 and interrupts the movement of the pilot motor and permits the rheostat arm 33 to return to its original position shown in Fig. 1. The energization of magnet 54 is sustained by closing contacts 87 and 88, the latter being connected by a wire 89 to the wire 53 which leads to magnet 54. When the lever 73 is made to assume the full line position shown in Fig. 1, the circuit breaker armature 79 is 130

raised to a position in which it will react more readily to an overload, the scale plate 81 being provided to indicate the current necessary to operate the armature 79 in various positions. Should the system be exposed to excessive load at any time, the upward movement of armature 79 moves the lever 23-82 to release the arm 21 which breaks open the contacts 19 and 21, deenergizes magnet 28, and opens the main motor circuit at contacts 43 and 44. If the field strength of the motor becomes weakened below a predetermined minimum, or if for any reason the field circuit becomes impaired or damaged, the holding in coil 65 releases armature 79 and breaks the circuit at contacts 11 and 12. This action also shuts down the motor if running, and if the motor is not running, said motor will not start under these conditions. If for any reason the motor stops by reason of a failure in the current supply, it will be ready to start up again under normal, fully protected conditions as soon as the current supply is reestablished. The leading advantages accruing to this system are that the acceleration in the motor's speed is dependent on the current input to the motor and not on the line voltage; such acceleration is fast or slow according to whether the current input to the motor is light or heavy, and is therefore absolutely automatic and self regulating. An abnormally weak field, an open circuit in the field, in its connections, in the field rheostat, or a faulty contact in the field circuit, causes the motor to stop, if running, and if not running, it will not start under these conditions. These results are accomplished without the blowing of fuses, or damage to the motor or to any of the apparatus. The circuit breaker is arranged to protect the motor while it is being started as well as while it is running. The undesirable but usual practice of operators in setting well known types of circuit breakers so as not to trip while the motor is being started, is obviated by this system. Among other fields of service, this invention is peculiarly serviceable for use in connection with forced draft blowing motors and ventilating sets on shipboard for example where much confusion, loss of time, blowing of fuses, and damage to apparatus in general is often occasioned by the reestablishment of current after a shut down. According to my invention such a motor will start from zero conditions as soon as current is reestablished. In radio work, it is especially desirable to start and stop the radio motor generator with certainty, with speed, and without damaging the motor or the starter. My invention completely protects the radio apparatus from delay or damage due to conditions in the motor field circuit and can be readily adapted for use on starting panels at present in use.

I claim:

1. In a system of the character described, a motor to be started and controlled, a starting circuit therefor, a running circuit, a relay for changing from the starting to the running circuit, an energizing circuit for said relay including separable contacts, a field energizing circuit, and a holding-in coil for operating said contacts included in said field energizing circuit. 75

2. In apparatus of the character described, a main motor, a pilot motor, a starting circuit for said main motor including a pilot motor field winding in series with the main motor armature, a running circuit for said main motor including a relay and a circuit breaker, and means under the control of said relay for controlling the operation of said circuit breaker. 80

3. In a system of the character described, a main motor, a starting circuit therefor, a pilot motor for controlling said starting circuit, an operating circuit for said pilot motor, a running circuit for said main motor, means under the control of said starting circuit for establishing said main motor running circuit, and means under the control of said main motor running circuit for breaking said starting circuit. 85 90

4. In apparatus of the character described, a main motor, a rheostat therefor, a pilot motor for operating said rheostat, said pilot motor, having a field winding connected up in series with said main motor during the starting period, a relay provided with a switch controlling the main motor starting circuit, a circuit breaker controlling the energization of said relay, a running circuit for the main motor, a second relay for controlling said running circuit, and means operated by the second relay for controlling the operation of said circuit breaker. 95 100

5. In a system of the character described, a motor, a running circuit therefor, a relay for controlling said running circuit, a starting circuit for said motor including a branch for energizing said relay, an overload circuit breaker for said running circuit, and means operated by said relay for changing the degree of sensitiveness of said overload circuit breaker. 110 115

6. In apparatus of the character described, a main motor, a starting circuit therefor, a pilot motor for controlling said starting circuit, said starting circuit including a pilot motor field winding and main motor armature, a running circuit for said main motor, a relay for controlling said running circuit, and an overload circuit breaker under the control of said relay. 120 125

7. In apparatus of the character described, a main motor having an armature and field winding, a rheostat for said motor, a pilot motor for operating said rheostat, a circuit for energizing the main motor armature, in- 130

cluding a pilot motor field in series with said rheostat, a relay, a circuit independent of the rheostat resistance for energizing said relay, a circuit under the control of said relay and independent of said rheostat and pilot motor field for energizing said armature, an energizing circuit for the pilot motor armature including separable contacts, means operated by said relay for opening 10 said contacts, and a circuit breaker which controls the energizing circuit for said relay, said circuit-breaker having a magnetic coil in circuit with the main motor armature.

8. In apparatus of the character described, 15 a main motor, a starting circuit therefor, a pilot motor for controlling said starting circuit, said starting circuit including a pilot motor field winding and main motor armature, a running circuit for said main motor, 20 a relay for controlling said running circuit, and an overload circuit breaker under the control of said relay, said starting circuit including a resistance branch which excludes said relay, and another branch which includes said relay but excludes said resistance branch.

9. In a system of the character described, 30 a main motor provided with an armature and a field winding, a holding-in coil in circuit with said field winding, a starting rheostat for the main motor, a pilot motor for operating said rheostat, an energizing circuit for said pilot motor including separable contacts subject to the control of said holding-in coil, said pilot motor being provided with a field winding in circuit with the armature of said main motor, a running circuit for said main motor, and a relay connected up in circuit with said separable contacts for 40 controlling said running circuit.

10. In a system of the character described, 45 a main motor provided with an armature and a field winding, a holding-in coil in circuit with said field winding, a starting rheostat for the main motor, a pilot motor for operating said rheostat, an energizing circuit for said pilot motor including separable contacts subject to the control of said holding-in coil, said pilot motor being provided 50 with a field winding in circuit with the armature of said main motor, a running circuit for said main motor, a relay connected up in circuit with said separable contacts for controlling said running circuit, other separable contacts in the pilot motor energizing circuit, and means operated by said relay for separating said other contacts, said relay being provided with means for closing a substitute circuit for maintaining the energization 60 of said relay.

11. In a system of the character described, 65 a motor, a starting circuit therefor, a relay, a running circuit for said motor under the control of said relay, said running circuit including separable contacts, a holding-in

coil for said contacts, a field winding for said motor in series with said holding-in coil, and a pilot motor for controlling said starting circuit, said pilot motor being provided with a field winding in series with the 70 armature of the first mentioned motor, and another field winding under the control of said relay.

12. In apparatus of the character described, 75 a main motor, a starting circuit therefor, a pilot motor for controlling said starting circuit, said starting circuit including a pilot motor field winding and main motor armature, a running circuit for said main motor, a relay for controlling said running circuit, and an overload circuit breaker under the control of said relay, said starting circuit including a rheostat arm, a magnetic clutch for connecting said rheostat arm to said pilot motor, and means under the control of said relay for breaking said starting circuit.

13. In a system of the character described, 90 a motor, a starting circuit for said motor, a circuit-breaker having an overload coil included in said starting circuit, a relay, means for breaking said starting circuit and energizing said relay, a running circuit for said motor established by said relay to include said overload coil, said starting circuit including separable contacts other than those in said circuit breaker, a holding-in coil for holding said other contacts closed, and a field winding circuit for the motor including 95 said holding-in coil.

14. In a system of the character described, 100 a main motor, a running circuit therefor, a relay for controlling said running circuit, a pilot motor armature, a starting rheostat for said main motor including an arm moved by said pilot motor armature, a field winding for said pilot motor armature connected up in series with said rheostat and the armature of said main motor, a branch circuit connected with said rheostat for energizing said 105 relay, a second field winding for said pilot motor armature, an energizing circuit for said pilot motor armature and second field winding, including separable contacts, and means operated by said relay for controlling 110 said separable contacts.

15. In a system of the character described, 115 a main motor, a running circuit therefor including a relay switch and a circuit breaker other than said relay switch, a starting circuit for said main motor comprising a rheostat branch and a second branch excluding said rheostat, a relay magnet included in said second branch for operating said relay switch, an overload coil included in said running circuit, an armature operated by said overload coil for operating said circuit breaker, and means under the control of said relay magnet for setting said overload armature in different positions with respect to 120 125 130

said overload coil for varying the sensitiveness of said overload circuit breaker.

16. In apparatus of the character described, a main motor provided with a field winding, a pilot motor provided with a field winding, a pilot motor operating circuit independent of said main motor and including said pilot motor field winding, a rheostat operated by said pilot motor, a second field winding for said pilot motor, a starting circuit for said main motor including said rheostat, said second pilot motor field winding and the armature of said main motor, a running circuit for the main motor, and means in circuit with the main motor field winding for controlling said main motor running circuit, said main motor starting circuit including a relay which controls the main motor running circuit and is under the control 20 of said running circuit controlling means.

17. In apparatus of the character described, a main motor provided with a field winding and an armature, a circuit for energizing said field winding independently of 25 said armature, a pilot motor having a field winding and an armature, a circuit including separable contacts for energizing said pilot motor armature and field winding, means included in said main motor field winding 30 energizing circuit for operating said separable contacts, a rheostat operated by said pilot motor, a second field winding for said pilot motor, a starting circuit for the main motor armature, including said rheostat and 35 second pilot motor field winding, and a running circuit for said main motor armature.

18. In apparatus of the character described, a main motor provided with a field winding and an armature, a circuit for energizing said field winding independently of 40 said armature, a pilot motor having a field winding and an armature, a circuit including separable contacts for energizing said pilot motor armature and field winding, means included in said main motor field winding 45 energizing circuit for operating said separable contacts, a rheostat operated by said pilot motor, a second field winding for said pilot motor, a starting circuit for 50 the main motor armature, including said rheostat and second pilot motor field winding, a shunt which short-circuits said pilot motor and rheostat, and a running circuit for said main motor under the control of 55 said shunt.

19. In a system of the character described, a main motor, a running circuit therefor including a relay switch and a circuit breaker other than said relay switch, a start-

ing circuit for said main motor comprising 60 a rheostat branch and a second branch excluding said rheostat, a relay magnet included in said second branch for operating said relay switch, an overload coil included in said running circuit, an armature operated by said overload coil for operating said circuit breaker, and means under the control of said relay magnet for setting said overload armature in different positions with respect to said overload coil for varying 70 the sensitiveness of said overload circuit breaker, a pilot motor for controlling said starting circuit, an operating circuit for said pilot motor, and means operated by said relay magnet for breaking said pilot 75 motor operating circuit.

20. In apparatus of the character described, a main motor, a starting circuit therefor, a pilot motor for controlling said starting circuit, an operating circuit for said pilot motor including separable contacts, a running circuit for said main motor, means under the control of said pilot motor for changing from the starting circuit to the running circuit, and means operated by the 80 first-mentioned means for operating said separable contacts in the pilot motor operating circuit, the first-mentioned means including a relay energized by the starting circuit and the second-mentioned means including a lever displaced by said relay and separating said contacts.

21. In apparatus of the character described, a motor, an energizing circuit for said motor, a relay for controlling said energizing circuit, an energizing circuit for said relay including a circuit-breaker, and means under the control of said relay for varying 95 the degree of sensitiveness of said circuit-breaker, said circuit breaker having an overload coil in said motor energizing circuit, an armature subject to said coil, and means under the control of said relay for changing the normal position of rest of said armature.

22. In a system of the character described, 105 a main motor, a rheostat for starting the same, a pilot motor for operating said rheostat, a circuit-breaker comprising separable contacts in circuit with said pilot motor and an overload coil, a starting circuit for 110 said main motor including a field winding for said pilot motor and said rheostat, a running circuit for said main motor, a relay for controlling said running circuit, and an energizing circuit for said relay including 115 said separable contacts.

JOSEPH E. FELLER.
